FLUID PRESSURE ACTUATED ARTICULATED BOOM

Frank L. Glashaw, St. Ignace, Mich.

Application September 22, 1950, Serial No. 186,291

1 Claim. (Cl. 214—147)

1

The present invention relates to improvements in fluid actuated apparatus, and more particularly to the type of apparatus which is adapted for use on tractors or the like having fluid pressure supply means.

An object of the present invention is to provide a device which will actuate a plurality of types of tools and which can be moved to a multiplicity of positions.

Another object of the present invention is to provide a device wherein a tool may be moved to any desired position by selectively operating pre-selected of a plurality of control valves in the fluid pressure system.

A further object of the present invention is to provide a tool actuating means which is adapted to operate various types of tools necessitating pivoting movement in their operation.

This invention also has for its objects to provide a fluid actuated apparatus which is positive in operation, convenient in use, easily mounted on a tractor or the like and easily disconnected therefrom, economical of manufacture, and of relative simplicity.

The means by which the objects of the present invention are accomplished include a frame which is adapted to be mounted on a tractor, a plurality of fluid cylinders hingedly mounted on the frame, a plunger in each of the cylinders, the outer ends of each of the plungers hingedly connected together forming a hinged joint, fluid pressure conduits connected to opposite ends of the cylinders, a source of fluid pressure for the fluid pressure conduits, and control valves in the fluid conduits for controlling the fluid pressure supply to the conduits whereby pressure may be selectively supplied to preselected of the cylinders effecting universal movement of the hinge joint.

Various other objects and advantages will become apparent from the detailed description to follow. In the description as well as in the claims, parts are at times identified by specific names for convenience, but such nomenclature is intended to be as generic in its application to analogous parts as the prior art will permit.

The best form in which I have contemplated applying my invention is illustrated in the accompanying drawings, wherein:

Figure 1 is a side elevational view showing the structure of the present invention positioned on a tractor;

Figure 2 is a top plan view of Figure 1;

Figure 3 is a detail view with parts in section showing the tool employed in combination with the present invention; and

2

Figure 4 is an elevational view showing the device mounted on the tractor; and

Figure 5 shows the details of the fluid pressure actuating system.

5 Looking more particularly to the drawings, wherein like numerals designate like parts throughout, numeral 10 designates generally the fluid pressure actuated apparatus of the present invention, numeral 12 designates generally a tractor or similar vehicle, and numeral 14 designates generally a tool which may be employed in combination with the present invention.

The fluid pressure actuated apparatus 10 includes a frame 16 mounted on the tractor 12, the combination of fluid actuated cylinder and plunger arrangements connected together and mounted on the frame 16, and a fluid pressure control system 20.

The frame 16 includes a base 24 supported by 20 the axle housing 22 on the tractor 12 by means of the U-shaped elements 26 having nuts 28 on their threaded ends engaging the flanges 30 of the base. A pair of upstanding members 32 and 34 are hingedly secured to the base 24, including 25 elements 36 and 38. The upper and lower ends of the upstanding elements 32 and 34 are connected by cross elements 37 and 40. The forward ends of the base 24 are adjustably connected to the upper ends of the upstanding elements 32 and 34 by means of telescoping adjusting members 46 and 48. The lower female ends 50 and 52 on the telescoping members 46 and 48 are hingedly connected to the base 24 at 42 and 44 and hingedly connected to the upstanding elements 32 and 34 at 54 and 56 by means of the inner male elements 58 and 60. The male and female members 46, 58 and 48, 60 are held in 30 adjusted relation by means of the pins 62 and 64 mounted in the members 50 and 52 and engaging 35 the apertures 66 and 68.

In order to give adjustability to the entire frame, the base 24 may be made longitudinally adjustable, or as shown, the tilting frame 32, 34, 37 and 40 may be hingedly connected at 39 to 40 the base 24. With this arrangement, the frame 45 may be easily mounted on tractors of varying size and easily disconnected therefrom.

As seen best in Figures 1 and 2, the fluid actuated pressure cylinder and plunger combination 50 18 include a plurality of major cylinders 70, 72 and 74, a secondary cylinder 76 pivotally mounted on the cylinder 72, and a tool actuating cylinder 78 mounted on the secondary cylinder 76 and hinge joint 80.

55 The cylinders 70 and 74 are provided with bifurcated ends 82 and 84 for hingedly connect-

ing the cylinders to the pivot elements 86 and 88 mounted at the upper ends of the upstanding elements 32 and 34. The other primary cylinder 72 is similarly provided with a bifurcated end 90 for connection to the hinge member 92 centrally mounted on the bottom element 37 of the tilting frame 32, 34, 37 and 40.

As seen best in Figure 1, each of the cylinders 70, 72 and 74 is provided with a plunger 94, 96, or 98, and all of the plunger elements 94, 96 and 98 are hingedly connected together forming a hinge joint at 80. The plunger 94 is provided with a flat apertured end 100, and the plunger 98 is provided with a flat apertured end 104. The plunger 96 is provided with a 30° (degree) flat apertured end 102. A bracket 106 is provided with a bifurcated portion 108 receiving the flat end 102 and the two flat ends 100 and 104 are positioned on the base 110 of the bracket 106. All of the flattened ends 100, 102 and 104, are hingedly connected together by means of the bracket 106 and bolts 112 passing through the apertures of the flattened ends and secured therein by means of nuts 114.

The secondary cylinder 76 is hingedly connected to the primary cylinder 72 by means of a split bracket 115 secured on the cylinder by means of bolts 118 and nuts 120.

The tool actuating cylinder 78 is hingedly connected to the hinge joint 80 by means of the bifurcated jack 122 secured to the upper end of the cylinder 78. The secondary cylinder 76 has its plunger 124 connected to the tool actuating cylinder 78 by means of the band 126 and nuts 128 holding the band 126 to the plunger 124.

The tool 14 includes a pair of bucket members 130 and 132 hingedly connected to bars 134 and 136 which are in turn hingedly connected to the bracket 138 which is mounted on the cylinder 78 intermediate its ends. Each of the buckets 130 and 132 has a flat bar 140 or 142 rigidly secured thereto and hingedly connected to the plunger 144 of the tool actuating cylinder 78.

The fluid pressure control system 20 includes a plurality of control valves 148, 149, 150, 152 and 154 each having conduits connected to a common source of pressure 156 which may be supplied with pressure from the tractor.

It is believed that from the foregoing description taken in conjunction with the drawings, the operation of the present invention will readily be apparent to one skilled in the art. By selectively operating a preselected control valve or control valves, preselected of the actuating cylinders are actuated, either extending or retracting the plungers mounted therein, effecting universal movement of the hinge joint and the tool operating cylinder 78. It will also be seen that by controlling the valve 148 the plunger 144 of the tool actuating cylinder 78 may be extended or retracted effecting opening and closing of the buckets 130 and 132 for obvious purposes.

By operating the valves 150 and 152, the plungers in the cylinders 70 and 74 are actuated causing the hinge joint 80 to be moved either to the left or to the right as desired. Actuation of the control valve 148 effects upward and downward

movement of the hinge joint 80, the hinge joint 80 pivoting about the hinge connections at 82 and 84. By means of the control valves 148, 150 and 152, the hinge joint 80 may readily be moved in any desired direction. If it is desired to pivot the tool 14 with respect to the hinge joint 80, the control valve 154 is actuated supplying pressure to the pressure cylinder 76 pivoting the cylinder 78 with respect to the hinge joint 80.

As hereinabove described, the tool actuating cylinder 78 is actuated by the control valve 146.

In operation, the tool 14 may be reciprocated with respect to the ground, pivoted with respect to the ground or rotated with respect to the ground, and the bucket members 130 and 132 may be opened with respect to each other at any desired time before digging or other operations.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

It should be further noted that the term "fluid" wherever used is to be interpreted in its broadest sense, that is, as defining any medium that may be placed under pressure and employed in a pressure actuating system.

Having described the invention, what is claimed as new is:

A fluid actuated tool carrying apparatus comprising a frame adjustably mounted on a vehicle, three fluid cylinders hingedly mounted on said frame in spaced apart relation, a plunger in each of said cylinders, the outer ends of said plungers being connected to a common hinge joint, a tool support mounted on said common hinge joint, a fourth cylinder, a plunger in said fourth cylinder, said fourth cylinder and plunger being connected between said tool support and one of said three cylinders, a source of fluid pressure, fluid conduits connected to each end of each cylinder, a control valve for each cylinder, said control valves selectively applying fluid to said cylinders to control said tool support.

FRANK L. GLASHAW.
